Patented Oct. 5, 1915.

UNITED STATES PATENT OFFICE.

ERVIN W. PINKERTON, OF ROCHESTER, NEW YORK.

COVER AND SPOUT FOR PACKAGES.

1,155,681.

Specification of Letters Patent.

Patented Oct. 5, 1915.

Application filed August 14, 1914. Serial No. 856,881.

To all whom it may concern:

Be it known that I, ERVIN W. PINKERTON, a citizen of the United States, residing at Rochester, in the county of Monroe and State of New York, have invented certain new and useful Improvements in Covers and Spouts for Packages, of which the following is a specification.

The object of this invention is to provide an improved cover and spout for such food packages as are used to contain staple articles, such as grape nuts, coffee, etc. This and other objects of my invention will be fully illustrated in the drawings, described in the specification and pointed out in the claims at the end thereof.

In the accompanying drawings, Figure 1 is a perspective view of the food package showing the cover thereof with my improved spout sealed against the cover. Fig. 2 is a perspective view of the food package in inverted position, showing the cover thereof, equipped with my improved spout, the spout being open for the purpose of pouring out the contents. Fig. 3 is a section on the line 3^x-3^x of Fig. 2. Fig. 4 is a view of the cover and spout looking at it from the inside of the package. Fig. 5 is a view of the spout shown in Fig. 4 closed up against the package. Fig. 6 is a plan view of the blank from which the spout is formed. Fig. 7 is a detail view of a portion of the blank showing a modification thereof.

In the accompanying drawings, like reference numerals indicate like parts.

In the drawings, reference numeral 1 indicates the food package and 2 indicates the top thereof.

3 is an opening in the top of the package made by simply cutting away the material of the cover, leaving however, sufficient material, integral with the cover to form the lugs or ears 4 and 5 on which the spout is pivoted. These lugs or ears will be turned down inside of the package. Mounted to swing on these lugs is a chute 6 formed of a single piece of stock for which purpose substantially the same material can be used as is used for the cover of the package.

The blank from which the spout is formed is shown in plan view in Fig. 6 and the dotted lines thereon indicate the lines on which the stock is bent in order to form the parts of the chute.

7 indicates the base of the chute and 8 in-

dicates the handle by which the chute may be operated.

9 and 10 are the flanges that form the sides of the chute and 11 and 12 are bent up to form stops which strike edgewise against the inside of the cover and limit the opening movement of the spout. The stops 11 and 12 may be finished at their outer edge with a margin that in the blank, would extend continuous with the sides 9 and 10, but it is preferable to cut them, slanting outward so as to give them an even bearing against the top when the spout is open and for this purpose the blank may be cut away as is shown in Fig. 6 or it may be cut with the added material shown in Fig. 7, in either of which cases, the stops would abut along their whole length against the cover when the spout is open. The sides 9 and 10 are perforated as shown at 13 and 14 and through these perforations and through the lugs 4 and 5, extends a pin 15 which forms a pivot on which the spout swings.

In Fig. 3, the spout is shown in its extended position ready to pour the contents of the package and in Fig. 5, the spout is shown folded against the top of the package and in Fig. 1, it is sealed over against the top of the package by a separate strip of paper 16 in which condition the package is put when it is filled and closed ready for shipment. When the purchaser wants to use the contents of the package, he will break away this paper seal 16, raise the spout as in Figs. 2 and 3 and pour the contents of the package. After a sufficient quantity has been poured from the package, the spout can be closed up against the top of the package to prevent dust and flies, etc., from getting into the package.

The paper cover that seals the opening and the spout can be printed with instructions as to the opening and use of the package.

The lugs 4 and 5 may be dispensed with and the ends of the pin 15 may be fastened directly in the top on each side of the opening by suitably bending it and passing it through the top or engaging it otherwise in any suitable manner.

While this invention is described in connection with a food package it will be understood that it may be used in connection with any other kind of a package, such as a tobacco package or packages that con-

95

110

tain any kind of products. It will also be understood that while this improvement will preferably be made of paper products it is equally adapted to be used in connection with packages made of metal or other materials.

I claim:

1. In a package, the combination of a top, an opening therein, lugs integral with the top on the opposite side of the said opening and bent at right angles to the top, a spout pivotally mounted between said lugs, said spout being folded from a blank and having a base and sides bent up from said base and stops bent at an angle to said sides, and having their ends adapted to abut edgewise against the top to thereby limit the swing of the spout.
2. In a package the combination of a top, an opening therein, lugs integral with the top on the opposite side of the said opening and bent at right angles to the top, a spout pivotally mounted between said lugs, said

spout being folded from a blank and having a base and sides bent up from said base, 25 and stops bent at an angle to said sides, and having their ends adapted to abut edgewise against the top to thereby limit the swing of the spout, perforations in said lugs and in said sides of the spout, a pin passing through said lugs and said sides pivotally connecting the spout to the top.

3. In a package, the combination of a top, an opening therein, a spout pivotally mounted in said opening, said spout being folded 35 from a blank and having a base and sides bent up from said base and stops bent up from said sides, said stops engaging edgewise with the top to limit the swing of the spout.

In testimony whereof I affix my signature in presence of two witnesses.

ERVIN W. PINKERTON.
